UNITED STATES PATENT OFFICE.

CAREY F. KIZER, OF WESTVILLE, OHIO, ASSIGNOR TO HIMSELF AND HEYLAS
D. LOUDENBACK, OF SAME PLACE.

MAIL-BAG.

SPECIFICATION forming part of Letters Patent No. 373,666, dated November 22, 1887.

Application filed October 8, 1887. Serial No. 251,814. (No model.)

To all whom it may concern:

Be it known that I, CAREY FRY KIZER, of Westville, in the county of Champaign and State of Ohio, have invented new and useful 5 Improvements in Mail-Bags, of which the following is a full, clear, and exact description.

The object of the present invention is to provide a means for closing the mouth of a mail bag or pouch that is most simple, cheap, readily 10 and easily closed and opened, requiring no straps and but one staple, and which is neat, durable, and most positively secure; and it consists in the formation and construction of the mouth of the pouch for its being closed and secured, all substantially as will hereinafter more 15 fully appear, and be pointed out in the claims.

Reference is to be had to the accompanying drawings, forming a part of this specification, in which similar letters of reference indicate 20 corresponding parts in all the views.

Figure 1 is a perspective view of the mouth of the pouch shown as open. Fig. 2 is a perspective view of the end of the bag with its mouth closed and secured, and Fig. 3 is a cross- 25 section at the closed mouth on line *xx*, Fig. 2.

In the drawings, *A* represents the bag or pouch, its rear side, *B*, extending higher than the front side, *C*, by an extended flap-piece, *D*, which is adapted to be folded in a line, as at *a*, 30 back from and parallel with its outer edge, and in a line with and opposite to the open edge *b* of the front side, *C*, and to lie over and outside of said edge *b*, closing the mouth of the bag. The rear side, *B*, of the bag, below the folding- 35 line *a* of its attached or extended flap *D*, and at its corner or near where it joins the front side, *C*, is provided with a staple or yoke-shaped stud, *E*, held in place upon a metal web or plate, *d*, lying upon and riveted to the 40 bag, and in a line below and parallel with the folding-line *a* of the flap-piece, at the same distance therefrom as the position of the stud *E*, the rear side, *B*, is provided with a series of holes, *F² F³ F⁴*, at equal distances apart. 45 (Shown as three in number.) The front side, *C*, of the bag, at the same distance below its mouth as the holes *F* are below the folding-line *a*, and opposite to said holes and the position of the staple *E*, being provided with a series 50 of four holes, *G G² G³ G⁴*, and the overlapping flap-piece *D* at the same distance outside of its

folding-line as the holes *F* *G* are below same, and in a parallel line thereto, has a series of holes, *H H² H³ H⁴*, all of said holes being properly bushed or protected by apertured webs *f* 55 of sheet metal, &c., riveted or otherwise secured to the material of the bag.

The bag constructed as described at its mouth permits, in its closing, the staple to pass through the hole *G*, as at *h*, Fig. 1, and the extended flap-piece *D* to be folded down to overlap the front side, *C*, with its one hole nearest its end also lying over the staple, and with the remaining three holes of each series all in coincident transverse lines. The mouth of the 65 bag, with its overlapping flap folded down, as described, is then folded in a longitudinal line, *g*, of the bag, midway between the staple and holes *G H* and the holes *F² G² H²*, the staple then lying through said holes. The mouth of 70 the bag is again folded longitudinally of the bag at a portion, *g²*, midway between holes *F² G² H²* and holes *F³ G³ H³*, the staple also lying through said latter holes, and again the bag is longitudinally folded at a portion, *g³*, midway 75 between holes *F³ G³ H³* and holes *F⁴ G⁴ H⁴*, said staple also lying through said latter holes and projecting beyond the face of the folded part a sufficient distance to receive a padlock or other fastening, the said folded portions between their respective holes lying in zigzag lines in relation to each other.

As shown, there are four folding portions of the mouth of the bag, to be folded on three longitudinal lines; but it is understood that 85 the number of folds may be increased or diminished, as desired.

Having thus fully described my invention, I claim as new and desire to secure by Letters Patent—

1. A mail bag or pouch formed of suitable flexible material, provided with a projecting stud or staple and one or more holes at and through its one side near and in a line parallel with its mouth, and holes in its other side opposite corresponding to and in a line parallel with the line of said stud or staple and said first-mentioned hole or holes, whereby when the sides of the bag are placed together the said latter-mentioned holes will lie over and in line with said staple and the first-mentioned hole or holes, and when the bag is folded longi- 90 95 100

tudinally between said staple and holes the staple may be passed through such coincident holes, substantially as and for the purpose described.

5 2. A mail bag or pouch formed of suitable flexible material, provided with a projecting stud or staple and one or more holes at and through its one side near and in a line parallel with its mouth, said side of the bag being provided with an extended flap-piece, D, having holes therein corresponding to and in a line parallel with the line of said staple and the first-mentioned hole or holes, the bag having holes in its other side opposite and corresponding to and in a line parallel with the line

of said staple and the first-mentioned hole or holes, whereby when the sides of the bag are placed together the said latter-mentioned holes will lie over the staple and the first-mentioned hole or holes, and when said flap-piece is folded down its holes will be over the staple and the holes of both sides of the bag, and when the bag is folded longitudinally between said staple and said holes the staple may be passed through said coincident holes, substantially as and for the purpose described. 20 25

CAREY F. KIZER.
